CLAIM

The ornamental design for a prayer kneeler with contoured, padded, body support surface, as shown and described.

DESCRIPTION

FIG. 1 is a front perspective view of our new design with padded body support surface shown;

FIG. 2 is a front perspective view with the padded body support surface removed for ease of illustration; and,

FIG. 3 is a rear perspective view with the padded body support shown.

The broken lines shown in the drawings are for illustrative purposes only and form no part of the claimed design.
